UNITED STATES PATENT OFFICE.

FRANKLIN ALLEN JUSTICE, OF PITTSBURG, PENNSYLVANIA.

CURTAIN-FRAME.

No. 824,484.

Specification of Letters Patent.

Patented June 26, 1906.

Application filed December 18, 1905. Serial No. 292,324.

To all whom it may concern:

Be it known that I, FRANKLIN ALLEN JUSTICE, a citizen of the United States of America, residing at Pittsburg, in the county of Allegheny and State of Pennsylvania, have invented certain new and useful Improvements in Curtain-Frames, of which the following is a specification, reference being had therein to the accompanying drawings.

10 This invention relates to certain new and useful improvements in curtain-frames; and the primary object of this invention is to provide an adjustable frame upon which one or more curtains may be stretched.

15 My invention aims to provide a curtain-frame which can be easily, quickly, and accurately adjusted to hold various sizes of curtains, and in this connection my improved frame is adapted to be used for stretching 20 curtains after they have been washed and cleansed to prevent them from shrinking and to maintain them in their proper shape until they have become thoroughly dried. To this end I have also devised novel means for 25 supporting the frame in an inclined position, said means being constructed to neatly fold into engagement with the frame, whereby said frame in its entirety may be collapsed into a compact and easily-handled form.

30 With the above and other objects in view, which will more readily appear as the nature of the invention is better understood, the same consists in the novel construction, combination, and arrangement of parts to be 35 hereinafter more fully described and claimed, and, referring to the drawings accompanying this application, like numerals of reference designate corresponding parts throughout both the views, in which—

40 Figure 1 is a perspective view of my improved frame, and Fig. 2 is a cross-sectional view taken on the line $\alpha\alpha$ of Fig. 1.

To put my invention into practice, I construct my improved frame of two end rails 1 45 and two sectional side rails 2 2, each side rail consisting of sections 3 and 4. The end rails and sections of side rails are provided with longitudinally-disposed slots 5, whereby the end and side rails may be adjustably connected together to form a rectangular frame adapted to support a curtain. The sections 3 and 4 of each side rail are connected together by screw-bolts 6 6, said bolts passing through the slots 5 5 of said sections and having their 55 ends provided with winged thumb-nuts 7, whereby the sections 3 and 4 of each side rail

can be firmly clamped together by rotating said thumb-nuts upon the screw-bolts 6 6. The outer ends of the side rails 2 2 are adjustably connected to the ends of the rails 1 1 by 60 similar screw-bolts and winged nuts 8 8 and 9 9, said screw-bolts passing through the slots of the end rails.

In order to secure a curtain within my improved frame, I provide the inner sides or 65 edges of the end and side rails with a plurality of hooks 10, having screw-threaded shanks 11, which engage in the rails. The hooks when not in use are turned whereby their hook-shaped ends will lie in a plane 70 horizontal with the rails 1 1 and 2 2; but when said frame is to be used the hooks are turned a quarter of a revolution, whereby their hook-shaped ends will extend upwardly to permit of a curtain being easily placed in 75 engagement with said hooks.

When the frame is used, it is necessary that means be provided to support the same in a vertical or inclined position, this being essential when the curtain stretched in said frame 80 is to be dried and bleached by the sun or in front of a stove or furnace. To support said frame in an inclined position, I provide the outer edges or sides of the end rails 1 1 with pivoted legs 12 12, said legs being adapted to 85 fold inwardly against the outer edges of said rails. To brace the legs when the frame is being supported in an inclined position, I employ toggle-levers 14 14, the edges of the end rails, together with the legs 12 12, being 90 cut away, as at 15 15 and 16 16, respectively, to accommodate the toggle-levers when the legs are folded inwardly against the outer edges of the frame.

To prevent the connected ends of the sections 3 and 4 of each side rail from sagging, I pivotally connect to one side rail, as at 17 17, telescopic braces 18 18, the free ends of said braces being adapted to engage the opposite rail and prevent one rail sagging relative to 100 the other. The telescopic braces 18 18 are adjusted by pins 19 19, and said braces are adapted to fold inwardly against the sides of the sections of the side rail to which they are pivotally connected.

To facilitate a person accurately adjusting my improved frame, I have graduated the sides of the end rails 1 1 and side rails 2 2, as at 20, said graduations insuring a rectangular frame being formed when the rails of said 110 frame are evenly adjusted in accordance with the graduations of said rails.

The manner of adjusting my improved frame is obvious; but I desire to call attention to the fact that when the frame is not being used the braces 18 18 can be folded 5 against their side rails, the legs 12 12 against their end rails, and the corner screw-bolts 8 8 and 9 9 loosened to permit of the frame being collapsed—that is, one side rail and one end rail being folded as close as possible upon the 10 other end rail and side rail—whereby an oblong and compact article will be formed of the frame, which can be easily stored away in a comparatively small space until it is desired to use the same.

15 I preferably construct my improved frame of light and durable wood; but the material from which the same is constructed is arbitrary, I simply having devised a collapsible and easily-adjusted frame, which can be 20 made of any desired size and any desired material.

What I claim, and desire to secure by Letters Patent, is—

A curtain-frame embodying two slotted end rails, two sectional side rails adjustably 25 connected to said end rails, legs pivotally connected to said end rails, toggle-levers pivotally connecting said legs and said end rails, telescopic braces pivotally connected to one of said side rails, the free ends of said braces 30 being adapted to bear against the other side rail, inwardly-extending revoluble hooks carried by all of the rails, means for adjusting said side rails, and means for adjusting said braces. 35

In testimony whereof I affix my signature in the presence of two witnesses,

FRANKLIN ALLEN JUSTICE.
